JOHN R. ACKERMAN, EDWARD B. CAMPBELL, AND NIRAM O. GOLDEN, OF DOBB'S FERRY, NEW YORK.

Letters Patent No. 76,966, dated April 21, 1868.

IMPROVEMENT IN LAMP-BURNERS.

The Schedule referred to in these Letters Patent and making part of the same.

TO ALL WHOM IT MAY CONCERN:

Be it known that we, JOHN R. ACKERMAN, EDWARD B. CAMPBELL, and NIRAM O. GOLDEN, of Dobb's Ferry, in the county of Westchester, and State of New York, have invented a new and improved Lamp-Burner; and we do hereby declare that the following is a full, clear, and exact description thereof, which will enable those skilled in the art to make and use the same, reference being had to the accompanying drawings, forming part of this specification.

This invention relates to improvements in that class of lamps in which kerosene-oil or other hydrocarbon-oils or liquids are burned, and which require a chimney to surround the flame in order to produce a perfect combustion, and prevent smoking. And it consists in the application and arrangement of a double cone, or cone and cylinder, which surrounds the wick-tube of the lamp, whereby the flame is supplied with atmospheric air or oxygen in sufficient quantity to produce perfect combustion, and prevent smoking, without the use of a chimney, as will be hereinafter more fully described.

Figure 1 represents an outside view of the burner of a kerosene-lamp constructed according to our invention.

Figure 2 is a vertical section of the same through the line *xx*.

Similar letters of reference indicate corresponding parts.

A is the ordinary wick-tube, and B is the base of the burner, which screws into the neck of the lamp. This part of the burner is made in the usual manner, only the tube A is elongated, as seen in the drawing.

C is a cone surrounding the tube, which is open around the base for the admission of air, as seen at *d*, and also open at its top end above the wick-tube, as seen at *e*.

The curve at the upper end of the cone conducts the current of air, which ascends within the cone, directly to the wick and flame of the lamp at the base of the flame.

D is a section of a cylinder with its lower end serrated, and its upper end conical in form, and open, as seen in the drawing.

In this example of our invention, the points *f* of the cylinder D are attached to the cone C, which leaves open spaces between the points for the admission of air.

The cylinder is also perforated below the conical top for the purpose of giving access to the air.

The air thus admitted within the cylinder D, is, by the conical top E, brought in direct contact with the flame of the lamp. This cylinder D may be constructed in different ways or shapes, and attached to the cone C in a different manner from that shown.

The perforations may be dispensed with, if desired, and other and additional provision may be made for the admission of air at its lower end or through its sides.

We are aware that many experiments have been made, (we have made many ourselves,) with a view to doing away with the very objectionable lamp-chimney, but hitherto no plan, (as far as we are aware,) has proved successful.

We can account for this in no way but upon the supposition that the carbon of the burning oil and the oxygen of the atmosphere have not been combined in proper proportions nor properly united to produce perfect combustion.

We, in the course of our experiments, have found that by extending the wick-tube, and surrounding it with a double cone, or cone and cylinder, or with two cylinders arranged substantially as we have described, we accomplish the object sought.

By the arrangement shown, an upward current of air is produced which not only supplies the flame with the requisite quantity of oxygen, but supplies it at the right time and place.

Having thus described our invention, what we claim as new, and desire to secure by Letters Patent, is—

The arrangement of the perforated cylinder D with relation to the open-bottomed cone C, conical top E and wick-tube A, as herein described, for the purpose specified.

JOHN R. ACKERMAN,
EDWARD B. CAMPBELL,
NIRAM O. GOLDEN.
